UNITED STATES PATENT OFFICE

BEN J. CHROMY, OF HOPKINS, MINNESOTA

INDUCTANCE UNIT AND METHOD OF COOLING

Application filed November 6, 1929. Serial No. 405,263.

This invention relates to electrical appliances in general. More specifically, this invention relates to inductance units and method of cooling inductance units.

An object of this invention is to provide an inductance unit which may be efficiently and readily kept at a low normal temperature.

Another object of this invention is to provide an inductance unit of tubular material thru which a gaseous medium is caused to flow and in which this medium is caused to suddenly expand and cool the unit.

Still another object of this invention is to provide an inductance unit of tubular material with nozzles having orifices progressively increasing in size thru, passing a gaseous medium under pressure thru the inductance unit and causing this gaseous medium to expand after leaving each of the nozzles and cool the inductance unit.

Other objects of this invention will be apparent to those skilled in the art to which this invention pertains from the following specification and the claims.

In accordance with this invention an inductance unit of tubular material, such as copper or similar tubing, is provided with one or more nozzles whereby a gaseous medium, such as air, carbon dioxide or similar mediums commonly used as refrigerants which is passed under pressure thru the tubing is caused to expand suddenly at the orifice of the nozzle against another gaseous medium and cool the tubing surrounding it.

This invention will be more clearly understood from a reference to the specification and the drawing, in which

Fig. 1 is a top plan view of an embodiment of this invention;

Fig. 2 is a sectional view in side elevation;

Fig. 3 is a detail view of a modified form of this invention, and

Fig. 4 is a cross-sectional view along the line 4—4 of Fig. 3.

Reference numeral 1 of Fig. 1 designates a piece of tubing circularly formed into a coil having inductive reactance. This tubing may consist of any such material as copper,

aluminum, zinc, nickel, etc., or any alloy thereof suitable for inductance units.

A pair of supporting members 2, which are of insulating material, such as synthetic porcelain, wax impregnated dried wood and the like, are positioned within the turns of the coil 1 as illustrated in Fig. 2.

The supporting members 2 are fastened at their extremities to panel members 3 and 4 which serve to rigidly retain the members 2 in position and support the coil 1.

A plurality of nozzles 5, 6 and 7 are provided at spaced intervals to the tubular coil 1. The nozzle 5, which is closest to the end 8 of the coil 1, at which end the supply of compressed gaseous medium is connected to the coil, is made smaller in size than either of the nozzles 6 and 7. The nozzle 6, which is positioned substantially half way between the nozzles 5 and 7, is larger than nozzle 5, but smaller than nozzle 7.

In operation a supply of compressed gas, such as air, carbon dioxide, or similar gases, such as are employed in refrigeration, is connected to the end 8 of the inductance coil 1 and the gas permitted to flow thru the coil. Upon passing thru the nozzle 5 the gas expands and thru a well known physical process absorbs heat from the surrounding walls of the inductance coil. The gas, however, is not permitted to expand to atmospheric pressure at the nozzle 5 but at a substantial pressure is passed thru the tubing of the coil to the nozzle 6, where the expansion and cooling process again takes place. After passing thru the nozzle 6 the gas circulates thru the coil to the nozzle 7, where the final expansion and cooling step takes place. It is, of course, understood that a smaller or greater number of these nozzles may be provided to an inductance unit, and that the number to be used depends to a large extent upon the size of the tube and the size of the inductance coil employed. More efficient operation of this system of inductance cooling is obtained when gases at relatively high pressures are employed or when gases are employed at temperature ranges in which they act as relatively imperfect gases.

According to Kelvin's and Joule's experi-

ments, the fall in degrees centigrade is given by the following expression, which was obtained from page 144 of "The Mechanical Production of Cold," by Sir James Alfred Ewing:—

$$0.276(P_1 - P_2) \left[\frac{273}{T} \right]^2$$

where P_1 and P_2 are the pressure, in atmospheres, before and after the gas expands through the nozzle, respectively, and T is the absolute temperature before expansion.

The expanded gas is taken from the inductance coil at the end 9. In cases where air or other harmless gas is used as a refrigerant it may be allowed to pass directly into the atmosphere from the opening 9, whereas in cases a harmful gas is used it is led back to the apparatus employed for compressing it upon its leaving the end 9.

Where it is desired to use air as the refrigerant and no connection between the compressing apparatus and the end 9 is employed it is highly desirable to connect the end 8 of the inductance coil 1 into the low high frequency potential part of the circuit in which the inductance coil is to be used.

In case the inductance coil is to be employed in a push pull power amplifier system it is desirable to connect the supply of compressed gas to a place substantially in the center of the inductance coil. The inductance coil is then formed of two symmetrical portions in corresponding parts of which the compressed gas expands and flows at a substantially equal rate.

Where it is found desirable not to cut the tubing used for the inductance coil and form the nozzles as illustrated in Figs. 1 and 2 the nozzles may be formed by partially flattening the tubing 10 as illustrated in Figs. 3 and 4. A small opening 11 which forms the orifice of the nozzle is left in the flattened section of the tubing. Orifices of different sizes are also made in different sections of the inductance coil when they are formed by flattening the tubing.

It will be observed that various modifications of this invention may be made without departing from the spirit and scope thereof and that, therefore, I do not desire to limit this invention to the exact details as set forth in the foregoing specification except in so far as they are defined by the appended claims.

What I claim and desire to secure by Letters Patent of the United States is:

1. In inductance units the combination of an electrically conducting member, a nozzle supported by said member, means for passing gas through said nozzle, said gas being caused to expand at said nozzle and cool surfaces of said conducting member.

2. In inductance units the combination of an electrically conducting member wound into a helix, a plurality of nozzles supported by

said member, means for passing gas through said nozzles, said gas being caused to expand at said nozzles and cool surfaces of said helical conducting member.

3. In inductance units the combination of an electrically conducting member, means supported by said member for cooling surfaces of said member, said means being associated with a supply of cooling medium adapted to cool said member through expansion. 70 75

4. In inductance units the combination of an electrically conducting member, means supported by said conducting member for cooling surfaces thereof, said means including a plurality of nozzles of progressively increasing size. 80

5. In inductance units the combination of an electrically conducting tubular member, means supported by said tubular member for causing gas passing thru said member to expand and cool surfaces thereof. 85

6. In inductance units the combination of an electrically conducting tubular member, means positioned within said tubular member for causing gas passing thru said member to expand therein and cool surfaces thereof. 90

7. In inductance units the combination of an electrically conducting tubular member, a nozzle formed in the walls of said tubular member, said nozzle functioning to cause gas passing thru said tubular member to expand and cool surfaces thereof. 95

8. In inductance units the combination of an electrically conducting tubular member, a plurality of nozzles formed in walls of said tubular member at spaced intervals, each of said nozzles functioning to cause gas passing thru said tubular member to expand and cool surfaces thereof. 100 105

9. The method of cooling tubular inductance units comprising the steps of passing a gas thru the tubular inductance unit and causing said gas to suddenly expand while passing thru said inductance unit and absorb heat from surfaces thereof. 110

In testimony whereof I affix my signature.
BEN J. CHRÖMY.
